UNITED STATES PATENT OFFICE.

DAVID WALKER, OF NEWARK, NEW JERSEY.

DESIGN FOR A STAIR-CARPET BUTTON OR FASTENER.

SPECIFICATION forming part of Design No. 20,661, dated April 7, 1891.

Application filed February 4, 1891. Serial No. 380,236. Term of patent 7 years.

To all whom it may concern:

Be it known that I, DAVID WALKER, a citizen of the United States, residing at Newark, in the county of Essex and State of New Jersey, have invented and produced a new and original Design for Stair-Carpet Buttons; and I do hereby declare the following to be a full, clear, and exact description of the invention, such as will enable others skilled in the art to 5 which it appertains to make and use the same, reference being had to the accompanying drawings, and to letters of reference marked thereon, which form a part of this specification.

15 In the accompanying drawings, which are deemed sufficient to illustrate the invention, Figure 1 is a front elevation of the newly-designed stair-carpet button; and Fig. 2 is a section of the same, taken on line *x*.

20 The leading feature of the design consists in a stair-carpet-fastening button which in front elevation presents to view the figure of

a Maltese cross and is convexed or has its circumferential edges turned rearward.

In said drawings, *a* indicates a round carpet-fastening button, the outer edges of which are turned rearward, as indicated in Fig. 2, said button having the usual central nail-perforation *b*. *c* is a Maltese cross ornamenting the face of said fastener, the said cross projecting slightly from the ground *d* of said fastener. The said ground is ornamented by radial scallops.

What I claim as new is—

The design for a stair-carpet button or fastener, as herein shown and described.

In testimony that I claim the foregoing I have hereunto set my hand this 16th day of January, 1891.

DAVID WALKER.
